UNITED STATES PATENT OFFICE.

ISIDORE BARSHATSKY, OF ROXBURY, MASSACHUSETTS.

METALLIC HEEL FOR SHOES.

1,413,889.

Specification of Letters Patent. Patented Apr. 25, 1922.

Application filed August 28, 1920. Serial No. 406,550.

To all whom it may concern:

Be it known that I, ISIDORE BARSHATSKY, a subject of the Russian Government, and a resident of Roxbury, in the county of Suffolk and State of Massachusetts, have invented a new and useful Improvement in Metallic Heels for Shoes, of which the following is a specification, reference being had to the accompanying sheet of drawing,

10 forming part thereof.

My invention relates to metallic heels for shoes and has for its object to provide a hollow metallic heel which is detachably secured to a heel plate with which the heel interlocks and by means of which the heel is secured to the shoe.

Another object of my invention is to provide a detachable heel for shoes which is secured to a plate provided on the shoe bottom for the purpose, said plate and said heel being so designed as to be normally self locking when assembled together for retaining the heel in secured relationship with the shoe and otherwise detachable for permitting the ready removal or disengagement of the heel from the shoe as may be required for repairing or replacing purposes.

Still another object of the invention is to provide a hollow metallic heel with a packing section at the bottom thereof wherein may be packed a suitable composition which is adapted to receive and retain nails or screws holding the leather or rubber lifts applied to the heel bottom.

35 Other objects and advantages of the invention will be gathered from the description following herein and considered in connection with the accompanying drawing, wherein the invention is shown embodied.

40 The terms employed herein are used in the generic and descriptive sense to designate the elements illustrated, and are therefore not primarily intended as terms of limitation.

45 Referring to the drawing:

Fig. 1 represents an elevational view of the heel section of a shoe shown supplied with my type of heel;

50 Fig. 2 represents a longitudinal sectional view taken through the shoe and heel shown in Fig. 1;

Fig. 3 represents a longitudinal sectional view of the top portion of the heel which is here shown removed from the heel plate;

55 Fig. 4 represents a diagrammatic sectional

view of the locking section of the heel and plate;

Fig. 5 represents a plan view showing the heel assembled and set with the heel plate;

Fig. 6 represents a transverse sectional view taken substantially on line 6-6 on Fig. 2;

Fig. 7 represents a plan view of the heel plate;

Fig. 8 represents an elevational view of the heel plate; and,

Fig. 9 represents a plan view of the front portion of the top of the heel.

Like numerals refer to like parts throughout the several views of the drawing.

The numeral 10 represents a lady's shoe to which is applied a metallic heel of my type as 11 which is preferably cast of aluminum to assure a light weight heel for the shoe, the shape of the heel being made 75 preferably according to the style in vogue.

12 represents the top of the heel which is scooped to fit the round of the shoe. 13 represents the angularly disposed plate groove which reaches from the front of the heel 14 80 clear around the inside of the heel as shown in Fig. 5 and lies in a plane which is angularly disposed to the plane of the top edge of the heel, as shown in Fig. 3, where it will be observed that as a result of same, a wedge

feature is supplied the top of the heel, the function of which wedge feature will be hereinafter more fully explained. 15 represents an intermediate partition wall which is provided in the hollow of the heel for 90 dividing off the interior of the heel into two sections, namely the top section 16 and the bottom section 17. Said partition 15 may be provided with the aperture 18 as shown in Fig. 6, if desired, which forms the abutment 95 flange 19 for the packing 20 which fills the bottom section 17 of the heel as shown in the drawing. 21 represents the packing retaining flange which is provided in the bottom section 17 of the heel for securely retaining the packing 20 in the heel. The packing 20 may be made up of any suitable composition as papier-mâché, fibre, wood pulp or any other suitable material preferably such as may be applied and packed in 105 the heel while soft and which would harden there and solidify sufficiently to receive and retain the nails or screws as 22 which are driven therein for associating the heel lift 23 with the heel 11. 24 represents the heel 110

plate tongue engaging and abutting wall which is provided the inner side of the front wall of the heel.

25 represents the heel plate which is preferably made of sheet metal as sheet steel for example and may be provided with the shoe engaging nails or clips 26 which may be made integral with the plate, as when stamped out of the plate itself, as shown 10 in the drawing or separate from the plate according as may be desired. Any suitable number of such nails or clips may be provided the plate 25 to suit the particular requirements, said nails or clips being positioned away from the edge on the plate to free the same to engage with the groove 13 of the heel 11. The plate 25 is further provided with the locking tongue 27 which is preferably made integral with the plate 15 as shown in the drawing and sprung therefrom in the opposite direction to the pointing of the nails or clips (Fig. 8). If desired said tongue 27 may be made separate from the plate proper and rigidly secured thereto in any suitable manner to become part thereof. The tongue 27 is preferably provided with the aperture 28 therethrough which will permit of the engagement therewith of a hooked tool with which to raise 20 and spring the tongue from the locked position with the abutting wall 24, as will be understood, for permitting the separation of the heel from the plate. For the same purpose if desired the front wall of the heel may be provided with the small opening 29 through which the rod 30, as shown 25 in Fig. 4, may be inserted and which rod may be used for springing the locking tongue 27 back to free the heel so that the same may be removed and separated from the plate. Said rod opening 29 may be plugged and covered with any suitable material, as wax for example, and in that manner may be entirely hidden and concealed from view.

It will here be observed that the top of the heel provides a U-shaped flange which is grooved internally around same and which slidably receives the heel plate therein. The plane of said groove, as previously described, is angularly disposed in relation to the plane of the top of the heel, and is so positioned in the heel as to bring the entrance of the groove substantially at 50 the top of the front wall of the heel, as shown in Fig. 3, whereby a wedge feature is provided the top of the heel, as the drawing indicates.

Having thus described the parts of my 60 invention in detail the manner in which the same may be employed is as follows:

It will first be noted that the top of the heel is preferably made the full width of the shoe and that the width of the heel plate 55 25 is made to reach within the full depth of

the groove 13 provided in the heel 11 therefor, as shown in Figs. 5 and 6.

Secondly, the locking edge of the tongue 27 of the heel plate 25 when the heel 11 is set with the plate is positioned to engage 70 with the abutting wall 24 of the heel 11, as shown in Fig. 2, and the width of the groove 13 of the heel is made equal to the thickness of the heel plate to assure a snug fit therebetween. 75

Bearing the above in mind it will be understood that the plate 25 may be easily and readily attached to the bottom of the shoe 10 by means of the clips or nails 26, as shown in Figs. 2 and 6; the position of said plate being gauged by the operator to suitably set the heel with the shoe, as shown in full, in Fig. 1, wherein the rear edge of the heel assumes the position under the shoe upper. Said heel plate may thus be secured 80 to the shoe to become permanently attached thereto with the side and rear edges of the plate freed from the shoe to receive the heel 11 thereon, as shown in Fig. 6. With the plate thus secured to the shoe and with the tongue 27 normally sprung out as shown in Figs. 1, 2, and 8 it will be understood that by engaging the heel groove 13 with the plate 25 the heel 11 may be slidably forced onto the plate and under the shoe. In doing so the arch section of the heel in passing the tongue will engage with the same and spring it upward, then when the heel assumes its set position with the plate 25, the tongue 27 snaps back into its abutting position with the heel and automatically locks the same with the plate and against further motion in relation thereto. The angular character of the groove 13 in relation to the top of the heel provides a tapering wedge 105 to the top of the heel which functions between the edge of the plate 25 and the shoe bottom to which the plate is attached, and necessitates forcing the heel on to the plate against the wedging feature thus established, when it will be understood that the top of the heel is forced to set against the shoe bottom and wedged into position therewith. In that manner the heel 11 becomes 110 securely and rigidly locked with the shoe and is so positioned and associated therewith as to take the weight of the wearer evenly around the top of the heel, whereby the heel becomes stabilized in relation to the shoe and prevented from giving or tipping over to the side. 115

It will thus be noted that the type of heel and plate herein disclosed is equally applicable to new as well as old shoes and that the same affords an inexpensive but reliable heel 125 arrangement more particularly for ladies' shoes. The peculiar combination of the parts thereof permits of the ready application and removal of the heel to or from the heel plate as the case may be and provides 130

a simple and practical heel unit especially for repair and replacing purposes. The heel may be finished off in any desirable color by the ordinary enamelling process and provides a dressy and rich appearance to the shoe with which the same is associated. It will further be noted that the heel necessarily will remain set with the plate once it is assembled and locked therewith and will remain so until the locking tongue 27 is disengaged from the abutting wall 24 of the heel. The disengagement of the locking tongue may be affected through the shoe by engaging the tongue and lifting the same out of engagement with the abutting wall or by inserting a rod 30 through the hole 29 and engaging the rod with the tongue and forcing the same to spring back out of engagement with the heel, when the heel may be slid off from the plate as suggested by the dotted position of the heel shown in Fig. 1.

While the preferred embodiments of my invention have been described in detail, it will be understood that I do not wish to be limited to the particular construction set forth, since various changes in the form, material, proportions and arrangement of parts, and in the details of construction may be resorted to without departing from the spirit and scope of the invention, or destroying any of the advantages contained in the same, heretofore described and defined in the subjoined claims.

35 I claim:

1. A shoe heel comprising a heel plate provided with a snap element and adapted to be secured to a shoe; a shaped heel having a U-shaped channel at the top thereof angularly inclined in relation to the plane of said top and adapted to slidably receive said heel plate within same and an abutting element co-acting with said snap element of said heel plate adapted to interlock with the latter for relatively locking the heel with or releasing the same from the plate at will.

2. A shoe heel comprising a relatively flat heel plate having a U-shaped outline and provided with a locking spring; and a shaped heel having a U-shaped and scooped top flange provided with a groove on the inner side thereof which is angularly disposed to the top plane of said heel and adapted to slidably receive said heel plate

therein at an angle with said top flange, and an abutting element adapted to engage with said locking spring when the heel is set with the plate for locking the two together.

3. The combination of a heel-plate adapted to be secured to a shoe bottom and provided with a latch element; and a hollow heel member provided with a recess internally therein for slidably receiving the edge of said heel-plate to include said plate within said heel member, and a latch abutting element adapted to interlock with the latch element of said heel-plate—said plate recess being angularly disposed to the top of the heel member to effect a wedging action with the latter for securely and wedgedly engaging the heel member in set relation with the shoe.

4. The combination of a metallic heel having a hollow top section provided with a U-shaped flange adapted to set adjacently to the shoe bottom, a U-shaped groove positioned within the hollow of the heel below said flange and angularly disposed to the plane of the top thereof; and a transverse abutting shoulder positioned at the inner front end of the hollow of the heel; and a heel-plate shaped to slidably fit within said groove, provided with a yieldable tongue member, adapted to engage with the abutting shoulder provided therefor in the heel when the plate is set in position therewith.

5. The combination of a hollow heel member, provided with a shoe abutting top at the upper portion thereof, a U-shaped channel beginning at the forward portion of the heel substantially at the top thereof and extending rearwardly around the inner wall of the heel below the shoe abutting top thereof and at an angle therewith to provide a wedging action with the heel, and an abutting element in the front wall of the heel; and a heel-plate adapted to be secured to a shoe bottom and shaped to slidably fit within said U-shaped channel of said heel member, provided with a yieldable tongue adapted to spring into abutting position with the abutting member of said heel member to retain the heel-plate in set position with said heel member.

In testimony whereof, I hereunto affix my signature this 25th day of August, 1920.

ISIDORE BARSHATSKY.
